OPENING AND CLEANING MACHINE FOR
FIBROUS MATERIALS

Sydney Maurice Freeman and Arthur Linnert,
Didsbury, Manchester, England, assignors to
The British Cotton Industry Research Association,
Didsbury, Manchester, England, a British association

Application December 5, 1946, Serial No. 714,222
In Great Britain December 4, 1945

8 Claims. (Cl. 19—89)

1

This invention relates to machines for opening and cleaning fibrous materials, in which the material is opened by a beater and conveyed by suction to a cage or pair of cages. The invention is particularly applicable to those machines in which, in place of the more usual bladed or spiked beater, use is made of a fine-toothed beater of the licker-in type and having a cylindrical foundation surface, and the customary grid below the beater is dispensed with. As is known, in such machines, a degree of openness can be obtained such that the cage suction is adequate to carry the material forward without the support of a grid, the high degree of opening and absence of the grid resulting in improved cleaning.

The object of this invention is to increase the efficiency of opening and cleaning machines, particularly those of the type just referred to, by improvements in the arrangements for collecting the fibrous material from the space below the beater where the separation of trash occurs, and conveying it to the suction cage or cages. In the customary type of machine where a pair of cages is used the upper surface of the beater is provided with a closely fitting cover extending, in the case of a pedal feed, from the feed roller to a stripping edge very roughly diametrically opposite the feed system, while from this stripping edge there extends a sheet forming the upper boundary of the region where the cage suction operates to convey the material, stripped from the beater, to the cages, this sheet finally terminating in pneumatically sealed contact with the upper cage or merging into a closely fitting cover for the upper cage.

According to the invention an opening and cleaning machine of the kind comprising a rotary beater, means for feeding the material to be opened to the beater and means for collecting the opened material consisting of a suction cage and a passage leading from the periphery of the beater to the cage is characterised in that the said passage includes a substantial space volume above the beater.

The improved machine aforesaid may be further characterised in that the said space volume extends substantially to the region of feeding of the material to the beater; or in that the lower boundary of the passage provides a substantial space volume below the beater; or in that the edge of the lower boundary of the passage adjacent to the periphery of the beater is adjustable radially and/or circumferentially of the beater.

According to one embodiment of the present

2

invention the stripping edge and beater cover are dispensed with, and by means of a specially designed cover a considerable space above the beater is incorporated into the region where the cage suction operates. One form of such cover consists of a sheet extending vertically from the feed roller to a point some inches over the level of the highest point of the beater surface, and then bending horizontally and extending to the upper cage where it merges into a closely fitting cover of the usual type.

With a cover of this type practically perfect stripping is obtained owing to the large extent of the beater surface over which centrifugal force operates to throw off the material into the region where the cage suction operates. Air inlets to the space above the beater may be provided for example by leaving a narrow gap between the cover and the feed roller.

20 According to a further feature of the embodiment of the invention there is provided a lower boundary to the region between the beater and the cages, in the form of a sheet extending from a point on the lower cage near the nip of the cages, to a point just under the lower surface of the beater; and means are provided for varying the position of the leading edge of this sheet as regards both the distance from the beater surface and the positions along the arc of the surface. 25 From this leading edge the sheet is preferably made to diverge immediately from the surface of the beater.

According to a still further feature of the embodiment of the invention, means are adopted to minimise external irregularities in the stream of material passing to the cages. These means comprise a series of longitudinal vanes or blades extending downwards from the cover and thus dividing the region adjacent to the cover into a 30 series of longitudinal channels. These vanes extend downwards so that over the beater they come within a short distance from it, while they extend longitudinally from the rearward part of the cover, near the feed region, to within a short 35 distance from the upper cage. Preferably use is made of blades of wedge-shaped section widest where they are fixed to the cover and narrowing downwards to a blunt edge, thus providing a series of longitudinal channels narrowing in an 40 upward direction.

In the application of the invention to the special type of machine referred to above, in which a grid is dispensed with, use is preferably made of a pedal feed, and immediately below it a member of the type described in Patent No. 2,403,384

so disposed that the material and trash struck from the feed pass through the gap between the edge of this member and the surface of the beater and are projected into the space below the feed system and contiguous portion of the beater, trash being deposited and the fibrous material with a certain amount of light dust being carried forward by the suction of the cages.

In the accompanying drawings:

Fig. 1 is a sectional side diagram and

Fig. 2 is a fragmentary perspective detail of one example of the invention.

Figs. 1 and 2 show the application of the invention to a machine for opening and cleaning in which raw cotton is fed from a travelling lattice through a pedal feed of the well-known "tandem" type to a fine-toothed beater and thence drawn by air suction to a pair of cages, after which it may be dealt with in any known manner, for example formed into a lap or delivered into a suitable receptacle.

In Fig. 1, a feed lattice 1 delivers the cotton through compression rollers 2 to a tandem pedal feed 3 of which 3¹ is the feed roller; the material then coming under the action of the beater 4 which is provided with fine teeth 4¹. A cover 5 extends over the beater, leaving a considerable free space above it, and extending to the upper suction cage 6. A portion 5¹ of this cover is situated above the roller 3¹ and is bolted through slots to a vertical portion 5² so as to leave a gap of adjustable width above the roller 3¹. Above the portion 5² the cover is shaped to form a sloping portion 5³ and after that a horizontal portion 5⁴ and this is continued in an upwardly sloping portion 5⁵ to form a cover of usual type for the upper cage 6.

A number of longitudinal vanes 7 of wedge shaped section having blunt edges 7¹ pointing downwards are fixed along part of their upper faces 7² to the horizontal portion 5⁴ of the cover 5. These vanes are shaped at one end to fit flush against the sloping portion 5³ of the cover 5, and at the other end they extend beyond the portion 5⁴ to near the periphery of the upper cage 6.

A sheet 8 forms the lower boundary of the region where the cage suction operates to convey the cotton forward from the beater 4. The forward portion 8¹ of this sheet extends to the lower suction cage 6¹ making contact with it through a leather flap 8². This portion is fixed to arms 8³ which pivot on a shaft 8⁴ which runs across the machine and is held in the frame sides. The rearward portion 8⁵ of the sheet 8 converges towards the surface of the beater 4 and terminates in the leading edge 8⁶. This portion has fixed to it at each side of the machine a slotted member 8⁷ which is bolted to the frame side through a slot 8⁸ in it, a sealing plate 8⁹ being provided to prevent the ingress of air. The slot in the frame side is collinear with the shaft 8⁴, and together with the slot 8⁸ allows of the required arc-wise and radial adjustment of the leading edge 8⁶. The portions 8¹ and 8⁵ of the cover 8 are adjustably bolted together along regions which are plane or conforming in curvature. To avoid protuberances on the upper faces of the plate 8 which might entangle the cotton, the portion 8⁵ is fitted above the portion 8¹ and screwed studs are welded on the underface of 8⁵ and slots provided in the portion 8¹. The portion 8⁵ carries a downwardly extending sheet 8¹⁰ which forms one wall of the dust chamber below the beater and to allow for the small motion involved in the adjustment of the leading edge 8⁶.

8⁶, the sheet may make contact with the floor of the dust chamber through a leather flap.

In conclusion, as is well known, in the operation of cleaning machines wherein a rotary beater having a substantially cylindrical foundation surface is fitted with a close-fitting cover the fan action of the beater results in the development of very high air pressure in the region between the beater and cover. In point of fact, a pressure gradient is created in such a way that the highest pressure under normal conditions is built up very near to the feeding-in device, and it is such high pressures at this point which give rise to many difficulties heretofore encountered in the operation of machines such as those herein referred to. Among such difficulties are the following:

1. The beater is not stripped of its cotton in time to prevent some of said cotton being carried around for more than a complete revolution, with consequent incomplete stripping of the beater.

2. Collection of cotton at the beater end, resulting in overheating of the bearings.

3. Blowing down of lint into the trash chamber below the beater.

4. Blowing out of cotton at the feed, which can completely disorganize the working of the machine.

On the other hand, applicants have discovered that by employing a cover of the construction herein described and placing such cover at a suitable distance from the beater, the air pressure between the beater and the cover is considerably reduced and as a result thereof all of the difficulties above enumerated are entirely overcome.

We declare that what we claim is:

1. An opening and cleaning machine for fibrous materials, comprising a high speed rotary drum-like saw-toothed beater, means for feeding the fibrous material to the beater, a collecting chamber including upper and lower covers which at one end partially embrace the beater, one of said covers partially closing any entry for air to the chamber in advance of the feed, and the other cover partially closing any entry for air to the chamber after the feed, and a suction cage at the opposite end of the chamber for receiving the fibrous material from the beater, said second-mentioned cover being sufficiently close to the beater and the first-mentioned cover being so shaped and spaced away from the beater that the suction cage can produce a condition of less than atmospheric pressure in the chamber including a zone extending against the said first-mentioned cover to the region of feed so as to permit air carried round by the beater at its periphery and checked at the feed by the incoming material, to return within the chamber against such first-mentioned cover to the suction cage, said second-mentioned cover converging toward the periphery of the beater thereby to provide an expanding or volute-shaped space in the chamber.

2. An opening and cleaning machine according to claim 1, further characterized in that the edge of the said second-mentioned cover adjacent to the periphery of the beater is adjustable radially of the beater.

3. An opening and cleaning machine according to claim 1, further characterized in that the edge of the said second-mentioned cover adjacent to the periphery of the beater is adjustable circumferentially of the beater.

4. An opening and cleaning machine according to claim 1, the edge of said second-mentioned

cover adjacent to the periphery of the beater being adjustable radially and circumferentially of the beater.

5. An opening and cleaning machine for fibrous materials, comprising a high speed rotary drum-like saw-toothed beater, means for feeding the fibrous material to the beater, a collecting chamber including upper and lower covers which at one end partially embrace the beater, one of said covers partially closing any entry for air to the chamber in advance of the feed and the other cover partially closing any entry for air to the chamber after the feed, and a suction cage at the opposite end of the chamber for receiving the fibrous material from the beater, said second-mentioned cover being sufficiently close to the beater and the first-mentioned cover being so shaped and spaced away from the beater that the suction cage can produce a condition of less than atmospheric pressure in the chamber including a zone extending against the said first-mentioned cover to the region of feed so as to permit air carried round by the beater at its periphery and checked at the feed by the incoming material, to return within the chamber against such first-mentioned cover to the suction cage, the edge of the said second cover adjacent to the periphery of the beater being adjustable relative to the beater.

6. An opening and cleaning machine according to claim 5, further characterized in that the edge

of the said second cover is adjustable radially of the beater.

7. An opening and cleaning machine according to claim 5, further characterized in that the edge of the said second cover is adjustable circumferentially of the beater.

8. An opening and cleaning machine according to claim 5, further characterized in that the edge of the said second cover is adjustable circumferentially and radially of the beater.
